B. R. CRAMPTON

LATCH

Filed April 9, 1928

UNITED STATES PATENT OFFICE.

BASIL R. CRAMPTON, OF GRAND RAPIDS, MICHIGAN.

LATCH.

Application filed April 9, 1928. Serial No. 268,763.

This invention relates to a latch for use in conjunction with swinging doors, particularly refrigerator doors. The latch mounted on the door is of the swinging lever type to freely swing in an arc of substantially ninety degrees and in a plane parallel to the face of the door, stops being used to limit the swinging movement of the lever in either direction. It is a primary object and purpose of the present invention to provide a novel construction of latch which when the door has been swung to open position may have the latch lever located either vertical or horizontal and, irrespective of what position the latch lever may occupy, it will automatically engage with the keeper therefor mounted on the door casing to securely close and hold the door in closed position. The invention comprises a latch of this construction having many novel features and arrangements of parts for effectively attaining the end stated and is an improvement over the structure shown in my pending application for patent, Serial No. 186,250, filed April 25, 1927.

An understanding of the invention may be had from the following description taken in connection with the accompanying drawing, in which,

Fig. 1 is a side elevation of the latch and keeper, the door being partly open.

Fig. 2 is a front elevation showing the latch in its released position, fragmentary portions of the door and door casing only being shown.

Fig. 3 is a front elevation showing a fragmentary portion of a door and door casing with the latch and keeper mounted thereon and with the latch in closed position.

Fig. 4 is a fragmentary horizontal section and under plan view, the plane of the section being substantially on the line 4—4 of Fig. 3.

Fig. 5 is a horizontal section through the latch and keeper substantially on the plane of line 5—5 of Fig. 1, and

Fig. 6 is a fragmentary section similar to Fig. 5, illustrating a slightly different form of construction of the latch.

Like reference characters refer to like parts in the different figures of the drawing.

The latch is connected to a door 1 near its free vertical edge, while the keeper used with the latch is secured to the door casing 2 near one edge of the door opening. The latch has a base 3 connected to the door by means of screws, integral with which is an outwardly extending post 4 having an integral overhanging horizontal arm at its upper end ex-

tending to one side thereof substantially parallel to the base 3. The opposite edges of the post provide stops 6 to limit the swinging movement of the latch lever mounted between said base and arm 5.

The latch lever 7 is a bar of metal located at a point between its ends between the overhanging arm 5 and the base 3, a pivot passing through said arm, lever and base whereby the lever is mounted for free swinging movement in a plane parallel to the face of the door to move through an arc of substantially ninety degrees, being limited in its movements in either direction by the stop shoulders 6. One end of the lever is formed with an off-set handle 8, spaced a distance from the front of the door that the fingers of the operator may be placed between it and the door. The opposite end of the lever, extending in the opposite direction from the pivot, comprises an arm 9 which in the horizontal position of the lever passes beyond the free edge of the door on which it is mounted. This is for the purpose of engaging with a keeper secured to the adjacent part of the door casing.

A lug 10 is cast integrally with the base 3 and extends outwardly therefrom through which a rod 11 is slidably mounted. At one end it is equipped with a head 12 against a side of which the lever 7 engages when swung to vertical position. The opposite end of the rod 11 is equipped with a second head 13, having an angular inner side 14, as shown. The rod 11, as it passes through the lug 10, may slide freely within the limits prescribed by the heads 12 and 13 coming against opposite sides of the lug, and any suitable means may be used to hold the rod from rotation.

The keeper includes a base 15 from which a post 16 extends outwardly for a distance, terminating in a head 17 of the form shown, depending below the outer end of the post. The head at its lower surface or edge 18 and at its inner side is formed with an upwardly and inwardly inclined edge 19, whereby a retaining hook is provided back of which the arm 9 of the lever is received to hold the door in closed position. The upward and inward inclination of the edge 19 causes the door to wedge tightly shut when arm 9 of the lever engages therewith.

In the construction shown in Figs. 1 to 5 inclusive the outer edge of the post 16 at its inner side is formed with a downward and inward incline 20. As an equivalent thereof and to serve the same purpose in the form

shown in Fig. 6, said post 16 near its outer end is provided with a laterally extending lug 21 which has a downwardly and inwardly inclined outer side 20^a corresponding in all respects to the inclined edge or side 20 previously described. The only difference in the attachment is that the keeper in the construction shown in Fig. 6 is located farther outward from the edge of the door than it is in Figs. 1 to 5 inclusive.

In either case when the door is in closed position and with the lever engaged with the keeper, as shown in Figs. 3 and 4, to open the door the lever handle is engaged and the lever 15 swung upwardly to the position shown in Fig. 2. When this movement occurs a side of the lever comes against the head 12 and moves the rod 11 with head 13 outwardly or to a position such that when the door is closed the 20 inner inclined side of head 13 comes against either the inclined side 20 or 20^a on the keeper depending on which type of keeper is used.

If the lever remains in vertical position, as 25 shown in Fig. 2, head 13 engaging with the side 20 of the post 16 or the side 20^a of the lug 21 causes the rod 11 to move longitudinally, whereupon the latch lever is swung in a clockwise direction to bring the arm 9 back of the 30 depending hook portion of the keeper.

If the latch should be in horizontal position, as may occur through accident or otherwise, the latching of the door and the engagement of the lever with the keeper occurs when 35 the door is swung shut. In such case the arm 9 strikes against the lower edge 18 of the head 17 with a resultant movement of the handle toward vertical position. This movement continues until the arm passes by the lower 40 point or nose of the head 17 or, as usually occurs, until the lever strikes against the head 12 on rod 11, whereupon the lever movement is reversed and the arm 9 brought under the depending hook portion of the keeper. In 45 either case the latch lever engages with the keeper on closing the door irrespective of the vertical or horizontal position of the lever, in either of which positions it may be.

The construction described is simple, practical, and efficient, and is economical to manufacture by reason of the few and simple parts used, which are easily fabricated and assembled.

The invention is defined in the appended 55 claims and is to be considered comprehensive of all forms of structure coming within their scope.

I claim:

1. In combination, a door, a door casing, 60 therefor, a keeper attached to the door casing, a latch lever pivotally mounted between its ends on the door having one end formed into a keeper engaging arm and the other into a handle, said lever being swingable in a plane

parallel to the face of the door from a vertical 65 to a horizontal position and vice versa, a guide lug extending outwardly from the door, a rod slidably mounted through said lug and having a head at one end against which the lever engages when it is swung to vertical 70 position acting to move said rod longitudinally, a second head at the opposite end of the rod having an inner cam side, said keeper being provided with a cooperating cam portion against which the cam side of said second 75 head engages when the door is closed to thereby move the rod longitudinally in the opposite direction from which it is moved when the lever is turned to vertical position.

2. In combination, a door, a casing therefor, a keeper attached to the door casing, a base attached to the door, a post extending outwardly from the base, a laterally extending arm at the upper end of the post substantially parallel to the base, a lever located between said base and arm and pivotally mounted thereon at a point between its ends, one end of the lever at one side of the pivot comprising a keeper engaging arm and the opposite end thereof being formed into a handle, a lug projecting outwardly from said base to one side and above the pivot of the latch, a horizontal rod slidably mounted through said lug against one end of which the lever engages when turned to vertical position, a head on the opposite end of the rod having a cam inner side, said keeper being provided with a cooperating cam portion for the cam inner side of said head to engage against when the door is moved to closed position to automatically move said rod longitudinally and thereby swing the lever to horizontal position.

3. In combination, a door, a casing therefor, a latch lever pivotally mounted between its ends on the door to swing in a plane substantially parallel to the front of the door, stop means for limiting the swing of the latch lever between a vertical and a horizontal position, a horizontal rod slidably mounted on the door adjacent the free vertical edge thereof above and to one side of the latch lever pivot, against one end of which the lever engages when turned to vertical position, a head on the opposite end of the rod having a cam inner side, a keeper having a depending hook portion secured to the door casing and having a lug projecting laterally therefrom in the path of movement of said head on the rod when the door is closed, said lug having a cam outer side to cooperate with the cam inner side of the head on said rod when the door is moved to closed position to thereby move said rod longitudinally in a direction to swing the lever to horizontal position.

In testimony whereof I affix my signature.

BASIL R. CRAMPTON.
